UNITED STATES PATENT OFFICE

ROBERT L. VAUGHN, OF CRESTVIEW, FLORIDA

DESIGN FOR A LADY'S HAND BAG

Application filed June 27, 1929, Serial No. 31,852, and in Canada April 4, 1930. Term of patent 7 years.

To all whom it may concern:

Be it known that I, ROBERT L. VAUGHN, a resident of the town of Crestview, in the county of Oskaloosa, in the State of Florida, a citizen of the United States of America, have invented a new, original, and ornamental Design for a Lady's Hand Bag, as fully set forth and described in the specification and drawings hereunto annexed.

Figure 1 is a front elevation of a lady's hand bag, showing my new design, and, Figure 2, is a side elevation thereof in open position.

I claim: The ornamental design for a lady's hand bag, substantially as shown.

ROBERT L. VAUGHN.
